UNITED STATES PATENT OFFICE.

EDMUND A. SCHADE, OF NEW BRITAIN, CONNECTICUT, ASSIGNOR TO THE STANLEY RULE & LEVEL COMPANY, OF NEW BRITAIN, CONNECTICUT, A CORPORATION OF CONNECTICUT.

JOINT FOR FOLDING RULES.

1,227,206.

Specification of Letters Patent.

Patented May 22, 1917.

Application filed December 30, 1916. Serial No. 139,766.

To all whom it may concern:

Be it known that I, EDMUND A. SCHADE, a citizen of the United States of America, residing at New Britain, Connecticut, have 5 invented a new and useful Joint for Folding Rules, of which the following is a specification.

This invention relates to folding rules of the so-called "zig-zag" type and has for its 10 objects generally to improve the pivot joints of such rules.

A special object is to overcome the fault which has been more or less prevalent in rules of this character consisting in the failure and breakage of the springs employed at the hinge joints of such rules.

In accordance with these objects I construct the joint with two hinge plates pivotally connected together by a pivot stud 20 and provide a spring for holding the hinge plates in frictional engagement, said spring having an opening through which the pivot stud passes and being of greatest width about said opening whereby it is made of substantially equal strength throughout its length and therefore not liable to breakage. The spring is of bowed construction and is seated in a depression in one of the hinge plates, said hinge plate having a projection 30 on its opposed face meshing in a corresponding recess in the other hinge plate and a special feature is the widening of the spring seat in the first hinge plate to accommodate the widened portion of the spring and the 35 cutting away of the side walls of the widened portion of said depression to prevent holding engagement at this point with the depression in the opposite hinge plate.

Other features will appear more fully as 40 the specification proceeds.

In the accompanying drawing I have illustrated the invention embodied in a practical and preferred form and wherein:

Figure 1 is a view in edge elevation of 45 the hinge joint between two adjoining rule sections.

Fig. 2 is a longitudinal sectional view of the same.

Fig. 3 is a drop perspective view of the 50 several parts which go to make up the joint.

Fig. 4 is a top plan view showing the spring seated in the depression provided for it in the hinge plate.

In the first two views where the joint is 55 shown in assembled condition, 5 and 6 design-

uate the adjoining end portions of two of the rule sections of a so-called zig-zag rule, said sections being recessed or hollowed out on their opposing faces as indicated at 7 to receive certain portions of the joint members. 60

8 and 9 designate the two so-called hinge plates which are secured to the end portions of the rule sections, the first plate having a depression 10 therein opposed to the recess 7 in the rule section to which it is applied so as to form in conjunction with said recess a chamber for the spring and having at its opposite or exposed face a projection 11 engaging in or meshing with a correspondingly shaped depression 12 in the exposed face of the other hinge plate 9. These hinge plates are usually constructed of sheet metal, in which case a depression in one face provides a corresponding projection on the opposite 75 face. The depressed portion of the second hinge plate 9 is therefore received in the recessed part of the rule section 5. The intermeshing portions of the hinge plates are preferably constructed as disclosed and 80 claimed in the Bodmer Patent No. 928,174, July 13, 1909, so as to interlock at the opposite end portions thereof and thus serve to hold the rule sections in proper longitudinal alinement. The hinge plates are perforated 85 as indicated at 13 to receive the shank of the pivot stud 14.

15 designates the spring for yieldingly holding the hinge plates in frictional engagement, said spring being of novel construction in that it is of greatest width at its central portion at 16 about the opening 17 for the pivot stud and tapers gradually toward the opposite ends thereof as indicated at 18. This spring furthermore is 90 preferably cupped or "bossed" up around the pivot opening as indicated at 19 to form a raised seat for the head 20 of the pivot stud. This spring is freely received within the spring chamber before described and 100 bears at its opposite ends in the spring seat provided by the depression 10 in the first hinge plate 8.

The pivot stud is shown secured in place by a washer 21 seated in a pocket 22 surrounding the extended end of the stud, said stud being riveted over the washer as indicated at 23. The opposite end or head of the stud is freely received within an opening 24 provided in the rule section 6. 105 110

To carry out the idea of the Bodmer patent of having the intermeshing portions engaged at their opposite ends, I have shown the sides of the depression 10, where 5 it has been widened at 25 to accommodate the widened central portion of the spring, cut away as indicated at 26 so that there will be no meshing action of the two hinge plates at this central point, the meshing and 10 interlocking being thereby accomplished wholly at the ends of said interlocking parts and the longitudinal alinement being therefore always maintained.

From the foregoing it will be apparent 15 that the rule joint of my invention is well protected against breakage or breakdown, that longitudinal alinement is always preserved and that the device as a whole is simple and practical.

20 What I claim is:

1. A rule joint comprising a pair of hinge plates, a stud pivotally connecting said plates and a spring holding said plates in frictional engagement, said spring being 25 relatively narrow at its opposite ends and wider intermediate its ends and provided further with an opening through said intermediate wider portion through which the pivot stud passes.

2. In a rule joint, a pair of hinge plates, a stud pivotally connecting said plates and a bowed spring holding said plates in frictional engagement, said spring being widest 35 at its intermediate portion and tapering in width toward the opposite ends thereof and provided with an opening in said widest intermediate portion receiving the pivot stud.

3. In a rule joint, a pair of hinge plates having intermeshing portions on the meeting faces thereof and one of said hinge plates having a depression in the back thereof to provide a spring seat, a stud pivotally connecting the hinge plates and a bowed spring mounted in the spring seat 45 aforesaid, provided with an opening receiv-

ing the pivot stud, said spring being of substantially greater width about said pivot opening than elsewhere and the spring seat being recessed and cut away to accommodate said widened portion of the bowed spring. 50

4. In a rule joint, rule sections having recesses in their opposed faces, a hinge plate secured to one rule section having a depression opposed to the recess in said rule section to form a spring chamber and provided on its opposite face with a projection, a second hinge plate secured to the other rule section and depressed into the recess in the face of said rule sections, the hinge plates having pivot openings therethrough, 60 a bowed spring seated in the spring chamber aforesaid and bearing at its opposite ends in the depression in the first hinge plate, said spring having an opening therethrough in the intermediate portion thereof 65 and being of greatest width about said opening, a headed stud passed through the openings in the spring and hinge plates with its head bearing on the widened intermediate portion of the spring, the first rule section 70 having an opening therein freely receiving said head of the pivot stud, the second rule section having a seat surrounding the end of the pivot stud and a washer mounted in said seat and receiving the extended end of 75 the pivot stud, said extended end of the stud being riveted over the washer to thereby secure the parts together.

5. A rule joint comprising a pair of hinge plates, a stud pivotally connecting said plates and a spring holding said plates in frictional engagement, said spring having a perforation for the pivot stud intermediate the ends thereof and being of greatest width about said perforation, said spring 80 being furthermore bossed up about said pivot opening and the pivot stud having a head bearing on the raised seat thus provided by the bossed up portion of the spring. 85

EDMUND A. SCHADE.
